UNITED STATES PATENT OFFICE.

DUNCAN C. HOOKER, OF FARMINGTON, CONNECTICUT, ASSIGNOR TO THE JOHNS-PRATT COMPANY, OF HARTFORD, CONNECTICUT, A CORPORATION OF CONNECTICUT.

WIRE-CLAMP.

1,180,397.

Specification of Letters Patent. Patented Apr. 25, 1916.

Application filed November 29, 1915. Serial No. 63,919.

To all whom it may concern:

Be it known that I, DUNCAN C. HOOKER, a citizen of the United States, residing at Farmington, in the county of Hartford and State of Connecticut, have invented a new and useful Improvement in Wire-Clamps, of which the following is a specification.

This invention relates to those clamps which are provided for connecting branch circuit wires with main circuit wires where the amount of current to be tapped is relatively small and soldered joints are not necessary. These clamps are chiefly used in connection with cut-out blocks, branch blocks, fuse blocks, meter testing blocks, switch blocks, rosettes, sockets and similar electrical devices.

It is common practice to peel a short section of the insulation off from the main wire and apply some form of mechanical clamp to the bared conductor. The principal objection to hitherto existing types of clamps has been that if the clamps were made so as to properly fit a small wire they were inapplicable to a large wire, and vice versa, if the clamps were designed to receive large wires they would not properly clamp small wires. This lack of adaptability has led to considerable trouble, time and consequent expense to the wireman, as it was necessary for him to hammer and bend the clamps in order to adapt them to a larger wire than that for which they were designed, or to fill in the interstices with sheet metal or short bits of wire in order to adapt them to smaller wires than that for which they were designed.

The object of the present invention is to produce a simple and cheap clamp which is so designed that it can be quickly manipulated by any one in such a manner that it will properly fit any size of wire in a range which practice has shown to be sufficient to cover all commercial conditions.

Figure 1 of the accompanying drawings shows a plan of a clamp which embodies the invention. Fig. 2 shows a side view of the device arranged to clamp large wires. Fig. 3 shows the same device arranged to clamp wires of intermediate size. Fig. 4 shows a side view of the device arranged to clamp small wires.

The clamp has a tap strap 1 of any desired length and width. This strap is stamped

of sheet brass or other conducting metal 55 with one end bent so as to provide a transversely extending V-shaped recess 2. The cap plate 3, formed of brass and substantially the same width as the strap plate, has one end flat and its other end stamped so as 60 to form a similar transverse V-shaped recess 4. The V-shaped end of the strap 1 is preferably somewhat larger than the V-shaped end of the cap 3. Extending through the strap and cap plates, and preferably 65 threaded into the former, is a screw 5, which may or may not be provided with a binding nut 6 having a rounded inner end. The perforations through the plates for the screw are so located that when the cap is 70 turned one way the V-shaped end of the cap will be opposite the V-shaped end of the strap, and when the cap is turned around its flat end will be opposite the V-shaped end of the strap.

To clamp a wire of large size the plates are put together so that the apexes of the two V-shaped ends will be opposite each other and will project in opposite directions (as shown in Fig. 2). When the screw is 80 turned in, or the nut is tightened, so as to bind the plates together, the wire will be tightly pinched at four points, thus making strong mechanical and efficient electrical contact. If the diameter of the main wire 85 is so small that when the parts are assembled in this way they fail to make a satisfactory mechanical and electrical engagement with the wire, the cap plate is swung around on the screw so as to bring its flat end opposite 90 to the V-shaped opening in the strap plate (as shown in Fig. 3). Then when the screw is turned in, or the nut is tightened, the wire will be gripped between two sides of the V-shaped recess in the end of the strap plate 95 and one side of the flat end of the cap plate. If the wire is too small to be efficiently clamped in this way the cap plate is removed and turned over so that the apexes of the two V-shaped ends will be opposite but will 100 project in the same direction (as shown in Fig. 4). Then when the screw is turned in, or the nut is tightened, the small wire will be bound by the apex of the cap plate against two sides of the V-shaped recess in 105 the strap plate.

The recesses in the two plates are V-shaped so there will be contact with the

wire at three points, when the parts are assembled for clamping a smaller wire (as shown in Figs. 3 and 4), and at four points when they are assembled for clamping a larger wire (as shown in Fig. 2), and thus insure sufficient mechanical contact to prevent heating. These clamps may be cheaply made in this simple manner in large quantities and used by any wireman for tapping 10 a main wire of any size in common commercial use, according to the conditions which are found at the point to be tapped.

This invention obviates the necessity of providing clamps of various sizes or requiring the wireman to bend the ends of the plates if the main wire is larger than the clamp is designed for, or fill in the spaces if the wire is smaller than the clamp is adapted for.

20 The invention claimed is:

1. A wire clamp consisting of a strap plate having a V-shaped end, a cap plate having one end flat and the other end V-shaped, and binding means pivotally connecting the cap plate at the middle of its length with the strap plate so that the cap plate may be turned around and bound to the strap plate with the V-shaped ends opposite each other, or with the flat end of the cap plate opposite and closing the opening in the V-shaped end of the strap plate, and

thereby provide for clamping wires of different diameters.

2. A wire clamp consisting of a strap plate having a V-shaped end, a cap plate 35 having a flat end and a V-shaped end, and a screw pivotally holding the cap plate to the strap plate and passing through the cap plate midway between its ends whereby the cap plate may be turned so its V-shaped 40 end is opposite the V-shaped end of the strap plate, or its flat end is opposite and closes the opening in the V-shaped end of the strap plate.

3. A wire clamp consisting of a sheet 45 metal strap plate having one end bent V-shape, a sheet metal cap plate having one end flat and the other end bent V-shape, the V-shaped end of the cap plate being smaller than the V-shaped end of the strap plate, and detachable means holding the plates together so that they may be assembled with the V-shaped ends adjacent to each other and opening in the same direction, or opening in opposite directions, or assembled with the flat end of the cap plate covering the opening in the V-shaped end of the strap plate, and thereby provide for efficiently 50 55 clamping wires of widely different diameters.

DUNCAN C. HOOKER.
